BOTTLE CAP REMOVER

Melville D. Truesdale, Greenwich, Conn.

Application April 30, 1938, Serial No. 205,309

15 Claims. (Cl. 65—46)

My invention relates to a bottle closure remover.

In removing the closures or tops from bottled goods which are of the carbonated type, there is often spillage of a considerable portion of the 5 contents of the bottle. This spillage or foaming over results in injury to furniture, rugs, table cloths, etc., and to the clothes of the user of the opener.

An object of the invention is to provide a simple 10 bottle top remover which will prevent injury to the clothes of the user, or to furniture, rugs, tablecloths, etc.

A further object of the invention is to prevent 15 overflow of the carbonated beverage from the bottle after the top has been removed.

Another object of the invention is to provide means for preventing squirting of the 20 contents of the bottle when the top is partially removed.

Yet other objects of the invention are to provide 25 a construction which is simple, cheap to manufacture, and which will accomplish the above indicated objects, while at the same time providing a device for removing bottle tops which is easy to operate and which can be used for a long period without replacement.

With these and other objects in view, which may be incident to my improvements, the invention 30 consists in the parts and combinations to be hereinafter set forth and claimed, with the understanding that the several necessary elements comprising my invention may be varied in construction, proportions and arrangements, without departing from the spirit and scope of 35 the appended claims.

In order to make my invention more clearly understood, I have shown in the accompanying drawings means for carrying the same into practical effect without limiting the improvements 40 in their useful applications to the particular constructions which, for the purpose of explanation, have been made the subject of illustration.

In the drawings:

Figure 1 is a top plan view of my bottle closure 45 remover;

Fig. 2 is a view in side elevation of my bottle closure remover;

Fig. 3 is a view taken along the line 3—3 of Figure 1, looking in the direction of the arrows;

Fig. 4 is a view taken along the line 4—4 of Figure 3, looking in the direction of the arrows;

Fig. 5 is a view taken along the line 5—5 of Figure 3, looking in the direction of the arrows;

Fig. 6 is a sectional view showing the position 55 of the parts when starting to remove the bottle

closure, the device being shown with its top open in dotted lines;

Fig. 7 is a sectional view of another form of my device with a transparent top;

Fig. 8 is yet another form of the device in which 5 the device is formed without any top.

Referring to the drawings I have shown in Figure 1 a body portion 1, which may be of some suitable material, such as aluminum. The body portion is somewhat cylindrical in conformation, 10 and may be made with flat surfaces 2 for purposes of ornamentation. Integrally formed with the body portion 1 is a handle 3. The handle 3 is provided at its top with a cut-out portion 4 in which is pivoted, at 5, a finger grip 6, which may 15 be integrally formed with a top 7 which is adapted to fit over an aperture 8 formed in the body 1.

The aperture 8 formed in the body 1 is covered at its upper extremity by the top 7, which may be formed with a groove 9 which fits over a lip 10 20 formed at the top of the body 1. The portion of the top of the body 1 adjacent the cut-out portion 4 in the handle 3 is made relatively thin and has no offset lip 10. This portion I have designated by the numeral 11.

The lower portion of the body 1 is formed with a retaining bulge 12, over which is adapted to fit a resilient rubber shield 13 having a strengthening bead 14. The rubber shield 13 is provided with an aperture 15. The rubber adjacent the 25 aperture 15 is also provided with a strengthening bead 16.

On the inner wall of the body 1 is formed a shelf 17 which carries a flat hook 18. The hook 18 is held in place on the shelf 17 by means of 30 downwardly projecting fastening elements 19 which pass through apertures 20 formed in the shelf 17. The hook 18 is adapted to engage under the bottle closure, which I have indicated by the 35 numeral 21, see Figure 6.

Adapted to bear on top of the bottle closure 21 is the lower edge of a beveled rib 22 formed in the aperture 8. The rib 22 forms the pivot above referred to. The lower edge of this rib is adapted to rest on the top of the bottle closure.

There is formed a projection or ledge 23 on the lower inside rear of the body or housing 1. This projection subserves a very useful function in that it causes the rear portion of the aperture 15 in the resilient shield 13 to be pushed down 40 well around the neck of the bottle during removal of the closure or cap 21. The projection 23 prevents the shield from engaging the bottle neck on a slant. Without the ridge 23, it was found that the shield often remained in a "corked" position 45 50 55

and leakage would occur around the neck of the bottle.

The opening 15 of the shield 13 places the neck of the bottle in the proper position for removal of the closure 21.

When the parts are in the position illustrated in Figure 6, a downward pressure on the handle 3 in the direction of the arrow will remove the bottle closure 21. The shield 13 will catch any carbonated beverage that spills out of the neck of the bottle. The top 7 will prevent any of the carbonated beverage squirting out against the user or on the floor or furniture. The top 7 can be lifted by pressure on the finger grip 6 to pivot the top on the pivot 5, and the opener is turned upside down in order to eject the cap removed from the bottle. The cap or closure drops out between rib 22 to the rear of the housing or body 1. Thus, if a considerable amount of fluid has gathered in the aperture 8, this fluid may be decanted by opening the top and pouring out the accumulated fluid through a spout 25 formed in the body 1, the seal around the neck of the bottle remaining until practically all of the liquid is decanted.

In Figure 7 is shown a modification in which the top 7 is composed of a transparent material 30. Otherwise the construction is the same as that heretofore described. In Figure 8 I have shown a construction in which the handle 3 is made without any cutaway portion and no top is provided. Otherwise, the construction is similar to that heretofore described.

This application is an improvement on the invention disclosed in my co-pending application Ser. No. 128,845.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

1. A device for opening bottle closures on bottles having necks, comprising a hollow body having an aperture therein, a closure lifting member in the body, a rib located below the top of the aperture in the body against which the top of the bottle closure is adapted to bear, and a resilient shield at the bottom of the body aperture having an aperture through which the neck of the bottle is adapted to project.

2. A device for opening bottle closures on bottles having necks, comprising a hollow body having an aperture therein, a closure lifting member in the body, a rib located below the top of the aperture in the body whose lower edge is adapted to rest on the top of the bottle closure, a resilient shield at the bottom of the body aperture having an aperture through which the neck of the bottle is adapted to project, and a ledge joined inside the body aperture at the rear thereof to assist in adjusting the shield over the neck.

3. A device for opening bottle closures on bottles having necks, comprising a hollow body having an aperture therein, a closure lifting member in the body, a rib located below the top of the aperture in the body against which the top of the bottle closure is adapted to bear, and a resilient shield at the bottom of the body aperture having an aperture through which the neck

of the bottle is adapted to project, the upper end of the body aperture being in free communication with the atmosphere.

4. A device for opening bottle closures on bottles having necks, comprising a hollow body having an aperture therein, a closure lifting member in the body, a rib located below the top of the aperture in the body whose lower edge is adapted to rest on the top of the bottle closure, a resilient shield at the bottom of the body aperture having an aperture through which the neck of the bottle is adapted to project, the upper end of the body aperture being in free communication with the atmosphere, and a ledge formed inside the body aperture at the rear thereof to assist in adjusting the shield over the neck.

5. A device for opening bottle closures on bottles having necks, comprising a hollow body having an aperture therein, a closure lifting member in the body, a rib located below the top of the aperture in the body against which the top of the bottle closure is adapted to bear, a resilient shield at the bottom of the body aperture having an aperture through which the neck of the bottle is adapted to project, and a pivoted top for the upper end of the hollow body.

6. A device for opening bottle closures on bottles having necks, comprising a hollow body having an aperture therein, a closure lifting member in the body, a rib located below the top of the aperture in the body against which the top of the bottle closure is adapted to bear, a resilient shield at the bottom of the body aperture having an aperture through which the neck of the bottle is adapted to project, a pivoted top for the upper end of the hollow body, and an upwardly projecting finger grip to pivot the top.

7. A device for opening bottle closures on bottles having necks, comprising a hollow body having an aperture therein, a closure lifting member in the body, a rib located below the top of the aperture in the body against which the top of the bottle closure is adapted to bear, a resilient shield at the bottom of the body aperture having an aperture through which the neck of the bottle is adapted to project, said shield aperture acting to guide the bottle closure into proper position in the body aperture.

8. A device for opening bottle closures on bottles having necks, comprising a hollow body having an aperture therein, a closure lifting member in the body, a rib located below the top of the aperture in the body against which the top of the bottle closure is adapted to bear, a resilient shield at the bottom of the body aperture having an aperture through which the neck of the bottle is adapted to project, a pivoted top for the upper end of the hollow body, an upwardly projecting finger grip to pivot the top, said shield aperture acting to guide the bottle closure into proper position in the body aperture.

9. A device for opening bottle closures on bottles having necks, comprising a hollow body having an aperture therein, a closure lifting member in the body, a rib located below the top of the aperture in the body adapted to rest on the top of the bottle closure, a resilient shield at the bottom of the body aperture having an aperture through which the neck of the bottle is adapted to project, a pivoted top for the upper end of the hollow body, and an upwardly projecting finger grip to pivot the top, and a ledge inside the lower rear of the hollow body con-

tacting with the shield to assist in adjusting the shield around the bottle neck.

10. A device for opening bottle closures on bottles having necks, comprising a hollow body having an aperture therein, a closure lifting member in the body, a rib located below the top of the aperture in the body having an inclined unbroken surface whose lower edge is adapted to rest on the top of the bottle closure, a resilient shield at the bottom of the body aperture having an aperture through which the neck of the bottle is adapted to project, said shield aperture acting to guide the bottle closure into proper position in the body aperture, and a ledge inside the lower rear of the hollow body contacting with the shield to assist in adjusting the shield around the bottle neck.

11. A device for opening bottle closures on bottles having necks, comprising a hollow body having an aperture therein, a closure lifting member in the body, a rib located below the top of the aperture in the body having an inclined unbroken surface whose lower edge is adapted to rest on the top of the bottle closure, a resilient shield at the bottom of the body aperture having an aperture through which the neck of the bottle is adapted to project, a pivoted top for the upper end of the hollow body, and upwardly projecting finger grip to pivot the top, said shield aperture acting to guide the bottle closure into proper position in the body aperture, and a ledge inside the lower rear of the hollow body contacting with the shield to assist in adjusting the shield around the bottle neck.

12. A device for opening bottle closures on bottles having necks, comprising a hollow body having an aperture therein, a closure lifting member in the body, a rib located below the top of the aperture in the body against which the top of the bottle closure is adapted to bear, a

resilient shield at the bottom of the body aperture having an aperture through which the neck of the bottle is adapted to project, a pivoted top of transparent material for the upper end of the hollow body.

13. A device for opening bottle closures on bottles having necks, comprising a hollow body having an aperture therein, a closure lifting member in the body, a rib located below the top of the aperture in the body against which the top of the bottle closure is adapted to bear, a resilient shield at the bottom of the body aperture having an aperture through which the neck of the bottle is adapted to project, a pivoted top of transparent material for the upper end of the hollow body, and an upwardly projecting finger grip to pivot the top.

14. A device for opening bottle closures on bottles having necks, comprising a hollow body having an aperture therein, a closure lifting member in the body, a rib located below the top of the aperture in the body against which the top of the bottle closure is adapted to bear, and a rubber diaphragm fitted around the bottom of the body aperture and having a centrally located aperture through which the neck of the bottle is adapted to project.

15. In a device for opening bottle closures on bottles having necks, a hollow body having an aperture therein, a handle integrally formed with the body, a closure lifting member in the body, a rib located below the top of the aperture in the body adapted to rest on the top of the bottle closure, a rubber diaphragm at the bottom of the body aperture and having a centrally located aperture through which the neck of the bottle is adapted to project, and a top for the upper end of the hollow body, said top being pivoted to the upper surface of the handle.

MELVILLE D. TRUESDALE. 40
